UNITED STATES PATENT OFFICE.

GEORGE WESTINGHOUSE, JR., OF PITTSBURG, PENNSYLVANIA.

MEANS FOR DETECTING LEAKS IN GAS-MAINS.

SPECIFICATION forming part of Letters Patent No. 312,542, dated February 17, 1885.

Application filed January 21, 1885. (No model.)

To all whom it may concern:

Be it known that I, GEORGE WESTINGHOUSE, Jr., a citizen of the United States, residing at Pittsburg, in the county of Allegheny 5 and State of Pennsylvania, have invented or discovered certain new and useful Improvements in Means for Detecting Leaks in Gas-Mains, of which improvements the following is a specification.

10 In the accompanying drawings, which make part of this specification, Figure 1 is a longitudinal central section through an underground gas-main with my improvements applied, and Fig. 2 a transverse section through the same 15 at the center of the detector-pipe.

15 My present invention relates to improvements of the class exemplified in Letters Patent of the United States, No. 306,556, granted and issued to me under date of October 14, 20 1884; and its object is to enable leakage within a determined length of an underground gas-main to be indicated by a single detector-pipe, and access of gas leaking from the main 25 to buildings contiguous thereto to be prevented.

30 My invention, generally stated, consists in the combination, with an underground gas-main, of a bed or partial casing of material substantially impervious to the passage of gas at low pressure, a superposed packing having a continuous series of intercommunicating interstices, and a detector-pipe leading from said packing to a point above the surface of the ground; also, in the combination, with an 35 underground gas-main, of a bed or partial casing of material substantially impervious to the passage of gas at low pressure, a superposed packing having intercommunicating interstices, a detector-pipe leading from said packing to a point above the surface of the ground, and a partition of material substantially impervious to low-pressure gas extending from the casing to or near the surface of the ground.

40 The improvements claimed are hereinafter 45 more fully set forth.

45 In the practice of my invention the gas-main 1 is laid in a bed, 15, of clay, cement, tar-paper, or other material which will oppose greater resistance to the passage of gas than 50 the earth in which it is inclosed, said bed sur-

rounding the main on its bottom and on its sides to or near its center, and that portion of the main which projects above the bed is inclosed in a loose packing, 16, of broken stone, gravel, or any other suitable material which 55 will present a series of intercommunicating interstices or spaces throughout. Said packing affording a comparatively free avenue for the passage of gas relatively to the bed 15 and the surrounding earth, gas which may leak 60 from the joints or branch connections will pass readily into and permeate the interstices of the packing 16, which is divided into sections extending over any desired lengths of the main by partitions 17, of material which will, similarly to that of the bed 15, oppose substantial 65 resistance to the passage of gas, said partitions extending upwardly from the bed 15 toward the surface of the ground. A detector and escape pipe, 4, extends from the packing 16 to 70 a point above the level of the ground, at which it may be conveniently accessible to an inspector, said pipe affording an avenue for the escape of gas that may leak into the packing, the presence of which can be readily detected 75 by the application of a light to the open end of the detector-pipe. The packing 16 may be readily removed and thereafter replaced, as required for the stoppage of leaks that may be evidenced by testing the detector-pipes, 80 one of which is provided for each section of the packing in the length of the main.

To guard against the penetration of gas leaking from the main into buildings adjacent thereto, vertical leakage-guards 17, of material which will oppose resistance to the passage of gas—as clay, cement, tar-paper, &c.—may be located along one or both sides of the main for such portions of the length thereof as may extend adjacent to buildings, said leakage-guards 85 extending from the bed 15 for a greater or less distance toward the surface of the ground. The resistance opposed by the leakage-guards will cause the gas that may pass 90 into the earth above the main to escape therefrom on the side of the guard farthest from the building, in lieu of permitting the same to pass freely through the earth toward the same, as would otherwise be the case.

I claim herein as my invention—

1. The combination, with an underground gas-main, of a continuous bed or partial casing of material opposing a greater resistance to the passage of gas than the earth through which the main passes, and inclosing the lower and side portions of the main, a packing of material having intercommunicating interstices or spaces, said packing extending continuously for a determined length of the main and inclosing the main above the bed, and a detector-pipe leading from said packing to a point above the surface of the ground, substantially as set forth.
2. The combination, with an underground gas-main, of a continuous bed or partial casing of material opposing a greater resistance to the passage of gas than the earth through which the main passes, and inclosing the lower and

side portions of the main, a packing of material having intercommunicating interstices or spaces, said packing extending continuously for a determined length of the main and inclosing the main above the bed, a leakage-guard of material of analogous character to that of the bed and extending vertically therefrom outside of the superposed packing, and a detector-pipe leading from the packing to a point above the level of the ground, substantially as set forth.

In testimony whereof I have hereunto set my hand.

GEO. WESTINGHOUSE, JR.
